UNITED STATES PATENT OFFICE

HARRY L. WOLLENBERG, OF SAN FRANCISCO, CALIFORNIA, ASSIGNOR TO LONGVIEW
FIBRE COMPANY, OF SAN FRANCISCO, CALIFORNIA, A CORPORATION OF DELAWARE

CHEMICAL TREATMENT PROCESS AND APPARATUS

Application filed December 18, 1930. Serial No. 502,701.

This invention relates generally to processes and apparatus for effecting chemical treatment of various fibrous materials. It has particular application to treatment by chemical liquor at an elevated temperature and at a pressure above atmospheric, as for example the treatment of wood chips with chemical liquor in the manufacture of wood pulp.

In the past it has been common to carry out chemical treatment of fibrous material by batch operations. For example in the manufacture of sulphate or kraft pulp, stationary or rotating digesters are charged with wood chips, together with the chemical treatment liquors. The charge is cooked at an elevated pressure and temperature until the pulp has been properly digested, after which it is removed together with the spent liquor, and a new charge introduced. The objections to batch processes are obvious. For a plant of a given capacity the apparatus required is relatively large and bulky, and is comparatively expensive to install and maintain. In the effort to reduce installation and operating costs larger units have been introduced but they have been found to involve increased difficulty in maintenance of uniform temperature and other conditions so that yield and quality of product have been adversely affected by increased size of batch units. A large amount of skilled labor is required because of the many operations involved in charging, cooking and discharging the digesters.

Even with careful manual supervision, it is difficult to secure adequate control and uniformity of products, because the essential conditions are not uniform throughout the treatment vessel, and also because determination of the optimum cooking condition depends upon inherently unsatisfactory methods of sampling and testing the pulp as it is being treated in the digesters. Thus it is not uncommon to secure relatively low yield and quality of finished product, due to causes such as overcooking of part of the charge that receives excessive chemical treatment. Such prior processes have also been inefficient and uneconomical due to the tremendous amount of steam required for a short interval at the

beginning of the cooking operation, thus producing an uneconomical load for the associated boiler plants. A relatively large amount of heat is also lost due to radiation losses from the large treatment vessels, and due to loss of steam when the pulp and spent liquor are discharged from the vessels by blowing down the steam pressure. This loss by blowing down of steam pressure can be appreciated when it is considered that the steam pressure in the cooking operation is usually carried out at about 100 pounds per square inch. The practice of blowing off to reduce pressure in the cooking operation also causes a loss of chemical, and makes it difficult to segregate fixed gases from the remainder of the blowoff.

In an effort to obviate the disadvantages of batch processes in the treatment of fibrous material, it has been proposed to devise apparatus operating continuously. To my knowledge no such continuous apparatus or process has proven commercially practical. Their failure is believed attributable to improper methods of introducing and removing the fibrous material, and to the absence of proper methods of control. Furthermore previous continuous methods have not properly impregnated the fibrous material with the treatment liquor prior to the cooking operation.

It is an object of the present invention to devise a commercially practical process and apparatus for the continuous treatment of fibrous material with a chemical liquor, which will obviate the disadvantages of batch processes, and which will overcome the principal defects of continuous processes which have previously been proposed.

It is a further object of the invention to generally improve upon continuous processes for the treatment of fibrous material whereby the fibrous material is introduced into and removed from the treatment chamber while the pressure within the treatment chamber is maintained above atmospheric.

It is a further object of the invention to devise a treatment process of the above character which will secure more uniform and

higher quality products, which will require very little attention, and which will be relatively economical in the use of steam and chemical.

5 It is a further object of the invention to devise such a process which will be characterized by pre-impregnation of the fibrous material with chemical liquor, prior to digesting the material at an elevated temperature.

10 Further objects of the invention will appear from the following description in which the preferred embodiment of the invention has been set forth in detail in conjunction 15 with the accompanying drawing. It is to be understood that the appended claims are to be accorded a range of equivalents consistent with the state of the prior art.

16 Referring to the drawing:

20 Figure 1 is a side elevation in cross section, illustrating apparatus suitable for use in carrying out the process of my invention.

25 Fig. 2 is a cross sectional detail illustrating the mechanism which I prefer to utilize at the point where the treated fibrous material is expelled from the apparatus.

30 In my invention in place of treating separate batches of solids with chemical solutions or liquors, I cause the fibrous material to be treated, together with the treating liquor, to continually advance along a predetermined path, while the chemical treatment progresses to completion. I have found that if fibrous material being subjected to chemical liquor is formed into a comparatively long upwardly moving compact column, treatment at different sections along the length of this column can proceed independently of the chemical actions along other sections. Thus in practice I continually supply fibrous material, such as wood chips, to the lower end of a relatively long upright treatment chamber. Material of this column 35 is subjected to the treatment liquor which is introduced into the column concurrently with and preferably at a point or points adjacent to, the introduction of chips. As the material progresses to the upper end of the chamber or to the point of delivery, the pressure applied is gradually decreased, and the chemical action proceeds to completion. At the upper end of the chamber the spent liquor and treated material are removed. As 40 will be presently explained, both for the introduction and for the removal of the fibrous material from the treatment chamber or vessel, the material is compressed to form relatively compact masses which serve as closures to maintain a pressure within the treatment chamber above atmospheric.

45 Referring to the drawing for a concrete example of apparatus which can be utilized in my system, I have shown a digester or digesting container 10, which is positioned up-

right and which is relatively long compared to its cross sectional area. For continuously introducing fibrous material to the lower portion of this chamber there is shown a rotatable screw 11 positioned within a suitable housing 12. A conduit 13, which can be substantially cylindrical, communicates between the discharge end of housing 12 and the bottom of treatment chamber 10. A hopper 14 is illustrated for introducing chips or other fibrous material into housing 12. Screw 11 is preferably formed in such a manner that it is not only a feed means, but also a means for compressing the fiber to a relatively compact mass. Thus as illustrated in the drawing the screw 11 is provided with a gradually decreasing pitch and is also tapered to fit the tapered housing 12. It is also possible to utilize a screw of proper design having simply a continuously decreasing pitch without resorting to a tapered construction, a tapered construction can be utilized with a constant pitch, a tapered hub can be employed with a straight screw of constant pitch, or various combinations of these design factors can be utilized. The results to be accomplished are the formation of a compact column of fibrous material maintained at a relatively high pressure, which is continually advanced thru conduit 13 to the bottom of treatment chamber 10. I have found that if such a plug or column within conduit 13 is sufficiently compact, it serves as an effective closure against pressure within the treatment chamber. In other words although liquor under pressure may penetrate the plug to a certain limited extent, the friction offered by the relatively compact fibrous mass is so great that no liquor flow thru or about the mass will occur. Since the design of screws adapted to compress fibrous material is well-known in the art, further disclosure concerning their construction is unnecessary. It may be pointed out however that for different operating conditions, as for example different fibrous materials, the screws must be designed accordingly.

50 The treatment liquor is preferably introduced at the bottom of the treatment chamber 10, adjacent the point at which the fibrous material is introduced thru conduit 13. For this purpose I have indicated pipes 16 communicating thru the bottom of treatment chamber 10.

55 Various expedients can be utilized for heating the contents of chamber 10 to an elevated temperature. For example I have indicated a plurality of pipes 17 distributed along the length of the chamber. For a purpose which will be presently explained, the lowermost point of introduction of steam or application of heat is preferably spaced a substantial distance above the bottom of the chamber. Instead of directly injecting steam it is obvious that steam jacketing can be employed.

To minimize heat losses a jacket of heat insulating material 20 is shown.

Arranged within the chamber 10 I preferably provide means for continually breaking up the compact mass of fibrous material as it is introduced, and for causing the fibrous material to progress toward the upper end of the chamber. Thus there is shown a shaft 18 extending longitudinally of the chamber, and mounted at spaced points along this shaft are inclined blades or flights 19. Certain of the blades 19 are grouped near the lower end of the shaft 18, to break up or mechanically disintegrate the compact column of fibrous material being introduced into the chamber from conduit 13. In operation shaft 18 is slowly rotated in a direction to cause flight 19 to continually urge the fibrous material upwardly.

20 The upper end of chamber 10 communicates with what can be termed a "goose neck" conduit 21, which forms a wier 22. The treated fibrous material together with the spent treatment liquor flows over wier 22 to the expelling means to be presently described, thus causing the liquor and fibrous material to maintain a substantially constant height within the treatment chamber.

The expelling means consists of a housing 23 in communication with conduit 21, and in which a rotatable screw 24 is disposed. Screw 24 is designed to have characteristics similar to screw 11 previously described in that it serves to compress the fibrous material. Housing 23 is provided with a perforated portion 26, which communicates with an outer closed liquor chamber 28. Pipe 29 communicates with chamber 28 for the removal of liquor, the pipe being provided with a valve 31, a trap, or equivalent device. Conduit 32, which can be substantially cylindrical, is formed at the discharge end of housing 23. For purposes to be presently explained a closure member 33 can be mounted adjacent the outer end of conduit 32, and the positioning of this closure member 33 can be controlled by a hydraulic piston and cylinder device 34 or equivalent means.

The expelling means described above receives spent liquor together with treated fiber flowing over wier 22. As this mass is compressed by screw 24 liquor is expelled into chamber 28 and withdrawn thru pipe 29. A sufficient amount of liquor is separated to enable the resulting mass to be compressed to form a compact column which is continually progressed outwardly thru conduit 32. This compressed mass is likewise sufficiently compact to form a closure against the pressure within the treatment chamber. The degree of pressure upon the mass being expelled thru conduit 32 can be controlled thru practical limits by urging closure member 33 with more or less force towards the conduit 32. Likewise when the apparatus is first started

in operation, closure member 33 can be forced into engagement with conduit 32, to serve as a closure to retain pressure within the treatment chamber.

In operating my apparatus, fibrous material, such as wood chips, is supplied to hopper 14, compressed by continuous rotation of screw 11, and continually advanced thru conduit 13 in the form of a relatively compact mass which serves as an effective closure 75 against pressure within the treatment chamber. As this mass progresses into the treatment chamber, it is broken up by flights 19 and at the same time it is mixed with a treatment liquor introduced thru pipes 16. The 80 temperature of the treatment liquor as it is introduced thru pipes 16 is not sufficient to immediately commence the cooking or digesting of the wood chips. Therefore while a given strata of wood chips is progressing upwardly from the bottom of the chamber to the lowermost of steam pipes 17, the chips are being thoroughly impregnated with the treatment liquor. As the same strata continues to progress upwardly thru the treatment chamber, the chips and treatment liquor are heated to an elevated temperature by the injection of steam, to carry out the cooking or digesting operation. By the time the same strata reaches the top of the treatment 95 chamber positioned to flow over wier 22, the cooking operation will have been completed, and the material is then discharged by screw 24 as has been previously described. As the apparatus is preferably operated in digesting wood chips, the temperature to which the liquor is heated is sufficiently high to maintain a gas pressure above atmospheric above the surface of the liquor. From time to time 100 gas can be removed thru pipe 36 to prevent accumulation of gas pressure in excess of that desired.

The relative proportions of liquor and fibrous material within the treatment chamber are preferably such that a sufficient 110 amount of liquor is provided for the cooking operation, without providing such an excess as might cause channeling within the chamber. In general I have found that the capacity of the apparatus is primarily determined by the dimensions of the cooking chamber, and the rate of progress of the material thru the chamber. The temperature, and other factors must be such that cooking is complete when the material reaches the top of the chamber. Screw 11 is then operated at such a speed as to furnish the amount of material that can be thoroughly cooked under the conditions established. Screw 24 is operated at such a speed as to assure removal of all 115 material reaching it over wier 22, within the practical limits of control of screw 11.

In addition to the other characteristics of my process and apparatus, it should also be noted that while the fibrous material is pro- 120

gressing thru the treatment chamber 10, it is continually subjected to lesser or decreasing pressures. This characteristic is conducive to a high quality product, and the higher pressure maintained at the lower portion of the chamber is conducive to efficient preimpregnation.

I claim:

1. A continuous process for the treatment of fibrous material in a closed chamber or vessel maintained under a pressure greater than atmospheric, comprising advancing the fiber into the chamber in the form of a compressed column which is sufficiently dry and so compact as to serve as a closure against the chamber pressure, separately introducing treating liquor into the chamber, and mechanically disintegrating the inner end of the compact column as it is advanced into the chamber.

2. A process for continuous treatment of fibrous material for removal of soluble constituents under more than atmospheric pressure and temperature, comprising introducing the fibrous material into the treating vessel in a continually moving column sufficiently dry and so compacted by pressure that frictional resistance prevents any outflow thru the moving column, simultaneously introducing the treating liquor under requisite pressure, continuously advancing the mixture of fibrous material and treating liquor upwardly in a moving column, heating the compact moving column of fibrous material and treating liquor, gradually reducing the pressure to which the contents of the treating vessel are subjected as they progress therethrough, effecting a substantial separation of spent liquor from the treated fibrous material, discharging the separated spent treating liquor, and discharging the treated fibrous material in a continually moving column so compacted by pressure that frictional resistance maintains the pressure in the treating vessel.

3. A process for continuous treatment of fibrous material for removal of soluble constituents under more than atmospheric pressure and temperature, characterized by the use of a relatively upright treatment chamber or vessel, said method comprising introducing the fibrous material into the treating vessel in a continuous moving column so compacted by pressure that frictional resistance prevents any outflow thru the moving column, simultaneously introducing treating liquor under requisite pressure, continuously advancing the mixture of fibrous material and treating liquor in a compact moving column, heating the compact moving column of fibrous material and treating liquor, gradually reducing the pressure to which the contents of the heating vessel are subjected, causing the spent liquor and treated fibrous material to discharge from the upper portion

of the treating vessel over a wier, effecting a substantial separation of spent liquor from the treated fibrous material, discharging the separated spent treating liquor, and discharging the treated fibrous material in a continuous moving column so compacted by pressure that frictional resistance maintains the predetermined pressure in the treating vessel.

4. A continuous process for the treatment of fibrous material, comprising causing the fibrous material to continually progress upwardly thru a zone in which the material is impregnated with a chemical liquor without cooking, and then causing the material together with the impregnating liquor to continue to progress upwardly thru a cooking zone.

5. In apparatus of the character described, an elongated upright treatment chamber adapted to be maintained under a pressure greater than atmospheric and to contain a treating liquor, a conduit having its one end communicating with said chamber and its other end open to the atmosphere, said conduit being adapted to receive a compressed column of fibrous material which is so compact and dry as to serve as a closure for pressure within the chamber, and means for continually forming said column and for continually advancing the same thru the conduit into the lower portion of the chamber.

6. In apparatus of the character described, an elongated upright treatment chamber adapted to contain a treating liquor and adapted to be maintained under a pressure and temperature greater than atmospheric, a conduit having its one end communicating with said chamber and its other end open to the atmosphere, said conduit being adapted to receive a tightly fitting column of compressed fibrous material which is so compact as to form an effective closure for the conduit to prevent outflow of liquor thru the column from the interior of the chamber, and means for continually forming said column and for continually advancing the same thru the conduit into the lower portion of the chamber.

7. In apparatus of the character described, an elongated upright treatment chamber adapted to contain a treating liquor and to be maintained under an internal pressure greater than atmospheric, means for continually introducing fibrous material into the lower portion of said chamber, and means for continually removing treated fibrous material and spent liquor from the upper portion of the chamber, said last means comprising means for effecting separation of spent liquor from the treated fiber, for compressing the resulting fiber to form a compact mass, and for continually expelling the compact mass thru a conduit to the atmosphere whereby the

compact mass serves as an effective closure against the pressure within the chamber.

8. In apparatus of the character described, an upright elongated treatment chamber adapted to be maintained under pressure greater than atmospheric and to contain a treating liquor, means for continually introducing fibrous material into the lower portion of the chamber together with treatment liquor, means for heating the contents of said chamber, means for expelling treated fiber and spent liquor from the chamber, and a wier located adjacent the upper portion of the chamber over which spent liquor and treated fiber are caused to flow to said expelling means.

9. In apparatus of the character described, an upright elongated treatment chamber adapted to be maintained under pressure greater than atmospheric, means for continually advancing a compressed column of fibrous material into the lower portion of the chamber, said column being so compact as to serve as a closure against the pressure within the chamber, means for introducing treating liquor under pressure into the lower portion of the chamber, means for mechanically integrating the inner end of the column of fibrous material as it is advanced into the chamber whereby the treating liquor is en-

trained with the fibrous materials and is caused to progress in the form of a column upwardly thru the chamber, a wier located adjacent the upper portion of the chamber over which treated fiber and entrained spent liquor is caused to flow, means for removing a substantial quantity of the entrained spent liquor from the treated fibrous material, a conduit thru which the resulting treated fibrous material is adapted to be discharged, and means for discharging the treated fibrous material thru said conduit in a compressed column so compact as to serve as an effective closure against pressure within the chamber.

10. A continuous process for the treatment of fibrous material characterized by an elongated treatment chamber, said method comprising continually progressing the fibrous material through said chamber in contact with treatment liquor, maintaining the pressure within the chamber above atmospheric, and heating the material to effect cooking of the same only during the latter part of its travel through the chamber, whereby during the first part of its travel preimpregnation of the fibrous material will be effected under pressure without substantial cooking.

In testimony whereof, I have hereunto set my hand.
